CLAIM

The ornamental design for an implantable access port, as shown and described.

DESCRIPTION

FIG. 1 is a perspective view of a first embodiment of an implantable access port;

FIG. 2 is a front elevation view of the implantable access port illustrated in FIG. 1;

FIG. 3 is a left side elevation view of the implantable access port illustrated in FIG. 1;

FIG. 4 is a top view of the implantable access port illustrated in FIG. 1;

FIG. 5 is a bottom view of the implantable access port illustrated in FIG. 1; and,

FIG. 6 is a rear elevation view of the implantable access port illustrated in FIG. 1.

The broken line showing in FIGS. 1-6 are included for the purpose of illustrating environmental structures only and forms no part of the claimed design.
